UNITED STATES PATENT OFFICE.

HORACE W. BOUCH, OF SIDNEY, PENNSYLVANIA.

RAIL-JOINT.

1,217,400.

Specification of Letters Patent. Patented Feb. 27, 1917.

Application filed August 9, 1916. Serial No. 113,985.

To all whom it may concern:

Be it known that I, HORACE W. BOUCH, a citizen of the United States, residing at Sidney, in the county of Indiana, State of Pennsylvania, have invented certain new and useful Improvements in Rail-Joints; and I do hereby declare the following to be a full, clear, and exact description of the invention, such as will enable others skilled in the art 10 to which it appertains to make and use the same.

This invention relates to improvements in railway rail joints.

One object of the present invention is to 15 provide a rail joint of novel construction which obviates the use of fish-plates and bolts.

Another object is to provide a simple and 20 cheap device of this character which is strong and durable in construction and which can be quickly and easily assembled and taken apart.

A further object is to provide a rail joint 25 which will firmly hold the meeting ends of the rails in proper alinement to prevent both vertical and lateral displacement.

Other objects and advantages will be apparent from the following description when 30 taken in connection with the accompanying drawing.

In the drawing:

Figure 1 is a side elevation of a pair of rails joined in accordance with my invention.

Fig. 2 is a horizontal longitudinal sectional view taken on the line 2—2 of Fig. 1.

Fig. 3 is a perspective view of the end of one of the rails.

Fig. 4 is a perspective view of the end 40 of the other of the rails.

Referring particularly to the accompanying drawing, 10 and 11 represent respectively the ends of a pair of railway rails. Each of the rails includes a base portion 12, 45 a web portion 13, and a tread portion 14.

Referring particularly to the rail 10, it will be seen that the base portion has secured thereto by means of the rivets 10' an angular plate 15 the vertical portion of 50 which is spaced from the web, as shown at 15', to form a socket. On the other side of the web, is a laterally projecting stud or pin 16, the same being preferably flat with its wider faces directed upwardly and down-

wardly, respectively, and secured to the web 55 of the rail by means of the rivet or bolt 16'. On one side of the web of the rail section 11 and secured to the base of the rail by the rivets 11', is a guide 17, in which is slidably disposed a bolt member 18. Carried by the 60 bolt member is an outwardly extending lug or fingerpiece 19, which plays in an elongated slot 20 in the guide, and which lug is used for the purpose of moving the bolt member into and out of the before-mentioned 65 socket in the web of the rail section 10. This fingerpiece is threaded and carries a nut 19', which is adapted to be screwed against the plate 17 to hold the bolt 18 against movement after having been properly engaged in the socket 15'. On the opposite side of the web of the rail section 11, is secured an elongated member 21, the same 70 extending beyond the end of the web where it is provided with an elongated slot 22 for 75 the reception of the before-mentioned stud or pin 16.

The slot 22 is of greater length than the width of the pin to permit of the slight longitudinal movement of the rails due to expansion and contraction. This member 21 bears resiliently against the side of the web of the rail section 10, when the parts are assembled and the bolt member is disposed within the socket of the said rail section, as 85 clearly seen in Figs. 1 and 2.

It will thus be seen that the bolt member firmly holds the rail ends from both vertical and lateral movement, thereby assuring a smooth and even surface across the joint 90 therebetween, and obviating the usual pounding when the car wheels pass over the joint.

In applying the rails together, the bolt is first retracted within the guide so that its 95 end is within or flush with the end of the web of the rail section, and then this section is placed, by a lateral motion, into alinement with the section 10, so that the stud enters the slot of the member 21. The 100 bolt is then slipped into the socket of the rail 10.

What is claimed is:

1. In a rail joint, the combination with the meeting ends of a pair of rails, the end 105 of the web portion of one of which is provided with a socket on one side thereof, a longitudinally slidable bolt mounted on the

- other rail for engagement in said socket, a longitudinally extending slotted member on the last named rail, and a stud carried by the first rail for reception in the said slotted member.
- 5   2. In a rail joint the combination with a pair of rail sections, the end of the web portion of one of said sections being formed with a socket, a laterally extending stud carried by said web, a slotted member carried
- 10

by the web of the other section and receiving the said stud therein, and a slideable bolt member arranged for engagement in the said socket.

In testimony whereof, I affix my signature, in the presence of two witnesses.

HORACE W. BOUCH.
